UNITED STATES PATENT OFFICE.

PRESTON C. GIBSON, OF GIRARD, ILLINOIS.

AUTOMOBILE-LIFTING DEVICE.

1,201,718.

Specification of Letters Patent. Patented Oct. 17, 1916.

Application filed April 29, 1916. Serial No. 94,405.

To all whom it may concern:

Be it known that I, PRESTON C. GIBSON, a citizen of the United States, residing at Girard, in the county of Macoupin and State 5 of Illinois, have invented certain new and useful Improvements in Automobile-Lifting Devices; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to new and useful improvements in lifting devices, especially designed for raising automobiles so as to relieve the tire of the weight of the machine 20 and thereby extend the life of the tires.

The invention consists of a simple and efficient device of this character having various details of construction, combinations and arrangements of parts which will be herein- 25 after fully described, shown in the accompanying drawings and then specifically defined in the appended claims.

My invention is illustrated in the accompanying drawings, in which:—

30 Figure 1 is a plan view showing parts in adjusted positions in dotted lines. Fig. 2 is a longitudinal sectional view. Fig. 3 is an end view. Fig. 4 is an enlarged detail view of one of the rack bars and adjacent parts.

35 Reference now being had to the details of the drawings by letter, A designate standards in which the parallel lifting rods B are journaled, and A' are supporting plates ex- tending beneath said lifting rods and trans- versely thereto.

40 An operating shaft, designated by letter F, is mounted in suitable bearings between and parallel to the lifting rods and a pair of pinion wheels H and H' are mounted near each end of the shaft 45 and rotate therewith. Collars L are also fixed to said shaft and one is mounted adjacent to each pinion, as shown in Fig. 2 of the drawings, said collars being of less diameters than the pinions. Rack bars K and K' have teeth upon their inner edges near their 50 ends and which mesh with said pinions, and the outer ends of said rack bars are connected with the knuckles of the toggle links D'

and E', and D and E respectively, the said links D' and D being connected each with 55 one of the lifting bars and operable in vertical planes transversely to the lifting rods. Each rack bar is provided with a pair of spaced straps, designated by letter N, at the inner ends of the rack bars, said straps ex- 60 tending from said bars around said shaft and engaging with the sides of the adjacent pinion and with the periphery of the collar adjacent thereto, to hold the teeth of the bars in mesh with the pinions. 65

A pinion O is fastened to the operating shaft and is in mesh with a pinion O³ mounted upon the stub shaft O⁴ in suitable bearings upon the frame, and O' is a pinion wheel which is fixed to the shaft O⁴ and is 70 in mesh with the pinion wheel O² upon the shaft O⁶, which latter has fixed thereto the crank R.

The operation of my invention will be readily understood and is as follows: The 75 parts being arranged in the manner shown in the drawings and the automobile positioned with the axles immediately over the bars B and C when the latter are at their lowest positions, the automobile will be bodily raised by the operator turning the crank 80 R in one direction, which will cause the gear wheels H and H' to rotate, driving the bars K and K' in opposite directions which will cause the toggle links to move to positions 85 in alinement with each other, as shown in dotted lines in Fig. 3 of the drawings, thus relieving the tire of the weight of the automobile. A reverse movement imparted to the shaft R will return the parts to their 90 normal positions.

What I claim to be new is:—

An automobile lifting device comprising 95 a pair of parallel lifting rods, a pair of supporting plates extending beneath said lifting rods transversely thereto, toggles connecting the ends of said lifting rods to said plates, said toggles operable in vertical planes transversely of said lifting rods, an operating shaft mounted between and parallel to said lifting rods, a pair of pinions on each end of said shaft, collars on said shaft, one on each side of each pinion, and of less diameter than said pinions, rack bars meshing at their inner ends with said pinions and connected at their outer ends with the knuckles 100 105

of said toggles, a pair of spaced straps on the inner end of each rack bar, said straps extending from said bars around said shaft and engaging with the sides of the corresponding pinion and with the peripheries of the collars adjacent thereto to hold said bar in mesh with said pinion, and means to rotate said shaft, whereby said rack bars are

caused to operate said toggles to raise or lower said lifting bars.

In testimony whereof I hereunto affix my signature in presence of two witnesses.

PRESTON C. GIBSON.

Witnesses:

E. A. GIBSON,
VIRGINIA McGHEE.
